UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

ELECTRIC SWITCH.

981,692.

Specification of Letters Patent. Patented Jan. 17, 1911.

Application filed March 19, 1900, Serial No. 9,208. Renewed December 23, 1901. Serial No. 86,980.

To all whom it may concern:

Be it known that I, HOWARD R. SARGENT, a citizen of the United States, residing at Schenectady, county of Schenectady, State 5 of New York, have invented certain new and useful Improvements in Electric Switches, of which the following is a specification.

This invention relates to improvements in 10 electric switches of the type shown in the patent to Deacon, 470,748, March 15, 1892, wherein a spring is compressed by the actuator while the contact maker is held against movement, and the contact maker 15 is released by further movement of the actuator, whereat the spring suddenly moves the contact maker.

Figure 1 is a section of a switch embodying my invention, together with its casing; 20 Fig. 2 is a plan of the switch on the base with the cover removed; Fig. 3 is a perspective view of the moving parts of the switch; Fig. 4 is a perspective view of a retaining piece; and Fig. 5 is a perspective view of a 25 modification of the switch movement.

In its simplest form this switch comprises only two moving parts, which perform in a novel and most simple manner the required function. These parts are the actuating 30 spindle A, and the contact carrier or cam C, a helical spring S being interposed between them, and tending to force the carrier positively parallel to the axis of the spindle. The contact-carrier C, as its name implies, 35 not only moves the switch contacts, but supports them.

Normally, the lower projection Q on the carrier C, engages with one of the projections r of the retainer R, which is fixed as 40 shown in a suitable manner in the switch casing, and the projection P on the spindle A bears against the cam surface H, and shoulder 1, of the carrier C. When the spindle A is rotated clockwise, the projection 45 P proceeds in the direction of the arrow away from the shoulder 1 and along the cam surface H, thereby lifting the carrier C to compress the spring S, and then removing the projection Q from engagement with the 50 projection r of the retainer R. At this time the spring S will tend to force the cam downward into its former position, and owing to the sharp incline of the cam-surface H, and independently of any tendency

it may have to rotate the carrier, it will in 55 fact, force the carrier C back longitudinally and parallel to the axis of the spindle A. But the projection P has been moved to a new position by the spindle A, and hence the spring S cannot force the carrier C back 60 to its former position, but this projection P will deflect the carrier C in an angular direction, and the lower projection Q on the carrier C will finally come to rest against the next succeeding projection r of the retainer R, and the shoulder 1 will again abut against the projection P on the spindle. This action would take place if the spring S were so mounted that it would tend to move the carrier C downward but the most 70 convenient manner of securing the lower end of the spring is to anchor it to the projection Q', and thus the spring will tend to force the carrier C to rotate as well as to force it downward. This rotary action 75 assists the cam-surface H in forcing the carrier to the lower advance position.

The contact piece 2 has a perforation through which the projection Q' extends, and the spring S bears upon the upper part 80 of the contact piece to keep it in position upon the carrier C. The projections Q and Q' are preferably the ends of a single pin which is passed through the carrier C. The spring S is of such a length that it will not 85 permit the projection P to be carried in a complete rotation to reengage with the shoulder 1, before the projection Q has been removed from the projection r of the retainer R. The same movement may be 90 embodied in a double-pole switch without essential modification, as will be clear to those skilled in the art.

In the case of the single pole switch shown, the contact carrier might be made in one 95 piece with the contact piece 2, but it is preferable for convenience in manufacture that they be made independently.

In Figs. 3 and 5, the turns of the spring S appear close together owing to the fact 100 that they are shown in perspective, but these turns are in fact separated from each other in their relaxed positions, as may be seen in Fig. 1.

The modification shown in Fig. 5 is substantially the same as that shown in the other figures. The difference is in the construction of the contact carrier C'. This

carrier has a cam slot H' in which the projection P plays, the upper edge of the slot serving the same purpose as the cam surface H shown in Fig. 3, and the lower edge 5 of the slot serving to prevent the carrier C' from moving upwardly, so that the projection P would slip from the shoulder 1 and play freely over the lower surface of the carrier C, thus causing the quick action of the 10 switch to be lost. In order to reduce the cost of manufacture, the carrier C' is formed of a metal punching, the ends of which are secured together by rivets 3, and which have a downwardly extending projection Q as in 15 Fig. 3. The contact piece 2 is secured to the carrier C' in a suitable manner, as by riveting or pinning to flared portions 4 of the carrier.

The handle 5 by which the spindle A can 20 be rotated is screwed to the end of the spindle and rests upon a suitable cover 6, which is supported upon an insulating base 7. Supported on the base are the binding posts 8, to which the circuit connections are made, 25 and which are electrically connected with the contact 9 with which the contact piece 2 engages. The lower end of the spindle A is cut as shown at 10 in Fig. 3, and a clip 11, shown in Fig. 1, is slipped in the cut 30 beneath the insulating base 7, to prevent the spindle A from moving vertically.

What I claim as new and desire to secure by Letters Patent of the United States, is,

1. An electric switch which comprises 35 movable and stationary contacts, an actuating spindle, a supporting carrier for the movable contact loosely mounted on the spindle and having a cam formation, a retainer, a spring which tends to force the carrier longitudinally along the spindle, and a projection on the spindle which upon rotation of the latter moves along the cam portion of the carrier to effect axial movement thereof, thereby putting the spring 40 under tension and removing the carrier from the retainer, whereat the cam portion permits the spring to force the carrier back along the spindle, and the projection on the spindle guides the carrier to a partial rotation about the spindle until it reengages 45 the retainer.

2. An electric switch which comprises 55 movable and stationary contacts, an actuating spindle, a supporting carrier for the movable contact loosely mounted on the spindle and having a cam formation, a retainer, a spring which tends to force the carrier axially along and angularly about the spindle, and a projection on the spindle 60 which upon rotation of the spindle moves along the cam portion of the carrier to move the latter axially, thereby putting the spring under tension and removing the carrier from the retainer, whereat the cam portion 65 permits the spring to force the carrier back

axially of the spindle and the projection on the spindle cooperates with the spring to force the carrier to partially rotate about the spindle until it reengages the retainer.

3. An electric switch which comprises 70 movable and stationary contacts, an actuating spindle, a retainer, a spring which is put under tension by the spindle, a supporting carrier for the movable contact having an inclined operating surface, and a projection on the spindle which upon rotation of the spindle forces the carrier axially of the spindle to put the spring under tension and remove the carrier from the retainer, whereat the spring forces the carrier directly back axially of the spindle, and the projection causes the carrier to move angularly until it engages an advance portion 75 of the retainer.

4. An electric switch which comprises 80 movable and stationary contacts, an actuating spindle having carrier guiding means, a retainer, a spring which is put under tension by the spindle, a supporting carrier for the movable contact having an inclined operating surface, and a projection on the carrier to which one end of the spring is fixed, the contact carrier being adapted to be removed from the retainer by the spindle and then forced back axially and angularly on 90 the spindle by the spring and guided by the spindle to partially rotate about the spindle until the carrier engages with an advance portion of the retainer.

5. An electric switch which comprises 100 an actuating spindle having carrier guiding means, a retainer, a spring which is put under tension by the spindle, a contact carrier having means whereby it is removed from the retainer by the spindle, and is then 105 forced directly back axially of the spindle by the spring and is guided by the spindle to move angularly until the carrier engages with an advance portion of the retainer, and a contact piece which is rotated by the carrier. 110

6. An electric switch which comprises 115 movable and stationary contacts, an actuating spindle having carrier guiding means, a retainer, a cam carrying the movable contact and loosely mounted on the spindle which is lifted by the guiding means from the retainer axially of the spindle when the latter is rotated, and a coiled spring secured to the spindle which forces the cam to move back angularly of the spindle to engage with an advance portion of the retainer.

7. An electric switch which comprises 125 stationary and movable contacts, an actuating spindle, a stationary retainer, a supporting carrier for the movable contact, a spring, and a pin and cam connection between the spindle and carrier whereby, when the spindle is rotated, the carrier is moved axially of the spindle out of engagement with the 130

- retainer, whereat the spring forces the carrier back angularly of the spindle into engagement with an advance portion of the retainer.
- 5 8. An electric switch which comprises movable and stationary contacts, an actuating spindle having a projection, a retainer, a cam supporting said movable contact and having a shoulder against which the spindle projection normally rests and mounted loosely on the spindle so as to be lifted from the retainer by the action of the said projection thereon upon rotation of the spindle, and a coiled spring secured to the spindle 10 which forces the cam to move back along the spindle and by means of the projection to be angularly guided into engagement with an advance portion of the retainer.
9. An electric switch which comprises 15 movable and stationary contacts, an actuating spindle, a cam supporting said movable contact and loosely mounted on the spindle, a stationary retainer, a projection on the cam which normally engages the retainer, a projection on the spindle which engages the cam to move the latter axially of the spindle, and a coiled spring secured to the spindle which forces the cam to move 20 angularly toward the retainer.
10. An electric switch which comprises 25 movable and stationary contacts, an actuating spindle, a retainer, a spring which is put under tension by the spindle, a supporting carrier for the movable contact provided with a cam slot, and a projection on the spindle which engages said slot to move the carrier axially of the spindle and out of engagement with the retainer, whereat the 30 spring forces the carrier back angularly of the spindle to engage an advance portion of 40 the retainer.
11. An electric switch which comprises 45 movable and stationary contacts, an actuating spindle having a projection, a retainer, a spring which is put under tension by the spindle, and a supporting carrier for the movable contact formed of a metal punching and having means whereby it is removed from the retainer by operation of the spindle projection thereon and then 50 forced by the spring directly back axially of the spindle and angularly thereon until it engages with an advance portion of the retainer.
12. An electric switch which comprises 55 movable and stationary contacts, an actuating spindle having a projection, a retainer, a spring which is put under tension by said spindle, and a supporting carrier for the 60 movable contact having a cam surface for engaging said spindle projection and formed of a metal punching with an integral projection, which projection normally engages with said retainer and is removed therefrom by the operation of the spindle 65 projection along said cam surface, whereat the carrier is then forced back axially of the spindle by the spring and guided by the spindle projection to partially rotate about the spindle until the integral projection on 70 the carrier reengages with the retainer.

In witness whereof I have hereunto set my hand this 16th day of March, 1899.

HOWARD R. SARGENT.
